UNITED STATES PATENT OFFICE.

OSCAR ANTON WIBERG, OF FINSPONG, SWEDEN.

RADIAL STEAM-TURBINE.

1,223,914.

Specification of Letters Patent. Patented Apr. 24, 1917.

Application filed January 15, 1917. Serial No. 142,525.

To all whom it may concern:

Be it known that I, OSCAR ANTON WIBERG, a subject of the King of Sweden, residing at Finspong, Sweden, have invented 5 certain new and useful Improvements in Radial Steam-Turbines, of which the following is a specification.

The present invention relates to radial flow elastic fluid turbines and specifically to 10 that type having a system of blades through which the motive fluid flows radially outward, and a second system of blades surrounding the first through which the motive fluid flows axially, the former system being 15 composed of blade carrying members that rotate in opposite directions, and the latter system of stationary fluid directing means and blades coöperating therewith, which blades also rotate in opposite directions with 20 those of the radial flow system. In such turbines the stationary blades or fluid directing devices for the axial flow portion have been rigidly and directly attached to the casing or to separate rings or supports rigidly se- 25 cured to the casing.

This rigid arrangement of the stationary blades is open to certain objections; viz., that it requires initially an accurate centering of the rotor and casing with respect to 30 each other which cannot be maintained during the repeated changes of temperature due to wide variations in load and to such changes as correspond to the working and non-working periods of the turbine. Owing 35 to the difficulty of maintaining the accurate centering of the coöperating parts under the conditions specified, it has been found necessary to provide relatively large clearances, especially in a radial direction between the 40 relatively rotating parts of the axial flow system, as, for example, between the outer ends of the rotating blades and the adjacent part of the turbine casing.

In this connection it should be borne in 45 mind that the outer casing is relatively cold as it delivers the exhaust directly into the condenser, and hence under normal conditions has a substantially constant temperature. The rotors receive high pressure high 50 temperature fluid at their center and discharge it outwardly, and hence there is a gradual fall in temperature from the inside

out. Since the load on a turbine varies widely at times it follows that the temperatures in different parts thereof vary with said changes and the more abrupt these changes are the more danger there is of distortion, accompanied by rubbing of the parts or enlargement of the clearances, or both, in different parts of the turbine. 60

The object of the present invention is to overcome the objections above noted, and to provide a supporting arrangement for the stationary fluid directing means which is unaffected, in so far as changes in clearances are concerned, by variations in temperature of the motive fluid whereby the initial clearances may be reduced and the leakage of motive fluid and consequent loss of power on the one hand, and frictional en- 70 gagement or rubbing of the parts on the other, avoided.

In carrying out my invention the stationary fluid directing means or blades instead of being rigidly attached to the turbine casing, as before, are attached to a ring or member which is supported by the turbine casing in such manner that it and the casing may freely expand and contract without the movements of one causing any displacement or distortion of the other. In other words, the support for the fluid directing means will change its diameter to the same, or substantially the same, degree as the rotor, and in substantially the same 85 period of time, with the result of maintaining the blade clearances substantially constant in amount at all times.

The means employed to support the member or ring from the turbine casing can be 90 made in a variety of ways, the essential feature being to allow the member to have certain amount of movement perpendicular to the turbine axis, but restrain it against lateral movement. In other words, expansions 95 and contractions in all radial directions should be uniform and unrestrained so that the ring will maintain its central position at all times.

In the accompanying drawings, Figure 1 100 is a longitudinal quarter section of a turbine illustrating one form of the invention; Fig. 2 is a sectional view of a portion of the same on a larger scale; Fig. 3 is a cross-

section of a modified form of the invention; Fig. 4 is an axial section of a further modification wherein an expansion ring is employed, and Fig. 5 is an axial sectional view 5 of a further modification.

a designates the turbine casing and *b* and *c* two shafts rotating in opposite directions and carrying the turbine disks *d* and *e* respectively, said casing being divided in an 10 axial plane as is usual in such machines. On the outer sides of the disks are concentric packing rings *d'* and *e'* extending between which are similar rings *d''* and *e''* carried by flat plates mounted in the turbine casing. 15 The purpose of this arrangement is to provide a means for balancing the end thrust on the disks, said packing rings serving to reduce the leakage. Motive fluid is admitted to the rotor through chests *a'* from which 20 it flows through suitable passages *a''* in the chests and *a'''* in the disks to the inner blades of the radial flow system. Mounted on the disks are axially extending blades *f* and *g* arranged in concentric rows and forming 25 the radial flow portion or system of the turbine. The disks are also provided with radially extending blades *h* and *i* which form a part of the axial flow portion or system of the turbine. Coöoperating with the blades 30 *h* and *i* are stationary fluid directing devices *k* and *l* of any suitable design which are mounted on an annular member or ring *m*. The inner ends of the directing blades are secured in any suitable manner to rings *l'* 35 and *l''* that closely surround these portions of the rotors carrying the radial flow blade system and serve to prevent leakage of motive fluid at this point. The ring *m* is substantially V-shaped in cross section and has 40 two outwardly curved surfaces *m'* and *m''* which direct the motive fluid from the radial flow system into the stationary blades of the axial flow system. The purpose of the curved surfaces is to avoid shocks and 45 eddies in the motive fluid and to gradually change its direction from radial to axial.

The ring or member *m* is supported from the turbine casing in such manner that both parts are free to expand and contract independently of each other, but relative axial movements are prevented. In Figs. 1 and 50 2 this is attained by the following means: Projecting inside the turbine casing is a ring, flange, or rib *r* which is suitably faced off on opposite sides and is supported from the casing by the studs or projections *p*. The purpose of using these projections as 55 distinguished from a complete annulus is two-fold, it permits of an equalization of 60 the pressures of the motive fluid exhausting on opposite sides and also permits of access to the securing means. The periphery of the central part of the ring is provided with a groove, the side walls of which engage the

faced portion or surfaces of the ring *r* and are free to slide radially thereon under temperature changes. Either as an additional support, or as a sole support, as requirements dictate, are radial pins *n* of which a plurality are provided. There should be at least 70 three of these pins and spaced equidistant. They serve to center the ring and also to guide it when moved in response to temperature changes. The pins may be fixed either in the blade carrying ring *m* or in the stationary part or parts *r* as desired, or they may be loosely arranged in both and provided with cross pins *o* to allow of only a certain limited longitudinal displacement. It is obvious that the pins *n* may be replaced 80 by radial guiding devices of any other form, for instance, dove-tail shaped projections protruding from one part and engaging correspondingly shaped projections extending from the other part. These pins also serve as a means to prevent the ring from turning due to the action of the motive fluid flowing through the guiding or directing blades. Owing to the fact that the flow of 85 motive fluid is equally divided left and right the axial thrust on the ring is balanced. 90

It is unnecessary for the guiding devices themselves to extend radially, as it is only 95 essential that they guide the blade ring in a direction perpendicular to the shaft axis. For instance, the arrangement shown in Fig. 3 may be employed wherein *m* represents the deflecting and blade carrying ring as before and *s* bars or links of suitable width 100 having enlarged ends which are seated in sockets in the ring and in the turbine casing or connected parts respectively. By arranging the bars or links as shown the ring *m* can freely expand and contract, but is always held in a central position with respect to the rotor axis. 105

In Fig. 4 is shown a modification wherein an expansion ring *t* is provided which is, or may be, slightly conical in shape. Its ends are enlarged to form circular anchoring devices which are seated on the one hand in a socket formed in a suitable part of the ring *m*, and on the other hand in a socket in a ring *t'* that is located in the turbine casing and secured by a calking strip *t''*. If desired, the ring may be slotted as at *t'''*. This figure also shows one of a number of braces between the rings *l'* and *l''* which unite the inner ends of the stationary guide blade. These braces may be made in a variety of ways. As shown, they are composed of rods *w*. 110

In Fig. 5 is shown a further modification in which the blade carrying member is supported by elastic means such as parts *t⁴* that form bridges, each of which is connected at its ends to the member and at its center to 115 120 125

the ring r which is supported by projections p from the turbine casing. The bridges should be relatively thin and long in the direction of the axis of the turbine so as to 5 give the desired elasticity.

By means of the arrangement above described I am able to definitely and exactly center the blade carrying ring m relative to the rotating parts, and said ring will always 10 remain in its central and proper position regardless of the expansions and contractions of the turbine casing. It is thus possible to reduce to a small value the radial clearances, especially those between the outer 15 ends of the blades h and i and the ring m , and also those between the rings at the inner ends of the guide blades and the coöperating surfaces on the two rotors. The clearances referred to are indicated at u and v in Fig. 4. 20 I have illustrated a certain construction or arrangement of parts herein whereby the motive fluid exhausting from the radial flow system is caused to decrease its residual velocity before entering the blades of the axial 25 flow system. This is not claimed herein as it forms the subject matter of my application, Serial No. 142,526, filed January 24, 1917.

In accordance with the provisions of the 30 patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:— 40 1. An elastic fluid turbine comprising a radial flow blade system, an axial flow blade system, stationary directing means which receive the fluid exhausting from the first system and deliver it to the axial flow system, 45 and an inclosing casing, in combination with means for supporting the stationary directing means from said casing which permit the casing and means to expand and contract independently.

50 2. An elastic fluid turbine comprising a radial flow blade system, an axial flow blade system, stationary directing means which receive the fluid exhausting from the first system and deliver it to the axial flow system, 55 and an inclosing casing, in combination with means supported by the casing and attached to said stationary fluid directing means which permit the casing and directing means to expand and contract independently and 60 prevent relative axial movement of the casing and said directing means.

3. An elastic fluid turbine comprising a radial flow blade system, an axial flow blade system, stationary directing means which re-

ceive the fluid exhausting from the first system and deliver it to the axial flow system, and an inclosing casing, in combination with an annular member which supports the fluid directing means, and means that connect the casing and member and permit them to expand and contract independently without changing the central position of said member. 65

4. An elastic fluid turbine comprising a radial flow blade system, an axial flow blade system, stationary directing means which receive the fluid exhausting from the first system and deliver it to the axial flow system, and an inclosing casing, in combination with an annular member which carries rows of 70 fluid directing means on opposite sides and has a deflector between, and means which are attached to the member and also to the casing which permit one of said parts to expand and contract independently of the 80 other. 75

5. An elastic fluid turbine comprising a radial flow blade system, an axial flow blade system, stationary directing means which receive the fluid exhausting from the first system and deliver it to the axial flow system, and an inclosing casing, in combination with a ring to which the directing means are rigidly attached, means for supporting the ring 90 from the casing which permits the ring and casing to expand and contract independently, and means for holding the ring concentric with the turbine axis when said expansions and contractions take place. 95

6. An elastic fluid turbine comprising a radial flow blade system, an axial flow blade system, stationary directing means which receive the fluid exhausting from the first system and deliver it to the axial flow system, and an inclosing casing, in combination with 100 a ring to which the fluid directing means are rigidly attached in sets, rings which unite the inner ends of said sets and occupy positions in close proximity to the rotors of said systems, and means for supporting the directing means from the casing which permits them to freely expand and contract independently but prevents relative axial movement. 105

7. An elastic fluid turbine comprising a radial flow blade system, an axial flow blade system, stationary directing means which receive the fluid exhausting from the first system and deliver it to the axial flow system, and an inclosing casing, in combination with 110 a ring to which the fluid directing means are rigidly attached, a support for the ring which is carried by the casing, and guiding means between the support and ring which permit one to slide on the other, and means to center the ring with respect to the blade system. 115

8. An elastic fluid turbine comprising a 120

radial flow blade system, an axial flow blade system, stationary directing means which receive the fluid exhausting from the first system and deliver it to the axial flow system, 5 and an inclosing casing, in combination with a ring to which the fluid directing means are rigidly attached, means projecting inwardly from the casing to form a support for the ring, and means that pass through

the projecting means and the ring to center 10 the latter.

In testimony whereof I affix my signature in presence of two witnesses.

OSCAR ANTON WIBERG.
